ROTARY PRESS AND LINT SAMPLER

Stuart W. Sinclair, Houston, Tex., assignor to Anderson, Clayton & Co., Houston, Tex., a corporation of Delaware

Original application May 16, 1961, Ser. No. 110,478, now Patent No. 3,122,089, dated Feb. 25, 1964. Divided and this application July 19, 1963, Ser. No. 311,932

5 Claims. (Cl. 100—89)

The present invention relates to an improved rotary press and lint sampler particularly useful in increasing the density of ginned cotton fibers and making a continuous sample of compressed cotton as it is being placed in a conventional press for baling.

This application is a division of the co-pending application of Stuart W. Sinclair entitled "Rotary Press and Lint Sampler," Serial No. 110,478, filed May 16, 1961, now Patent No. 3,122,089.

Although the present invention is particularly described hereinafter with reference to cotton fiber, it will become apparent that the present invention is useful in increasing the density of any compressible fiber lint and making a continuous sample thereof. The present disclosure is directed, therefore, to a rotary press and sampler for cotton, but it will be understood that other fibers and lints are encompassed within the scope hereof. To understand the theory of the present invention and the state of the cotton press art, a summary is given.

When raw cotton reaches the gin, it is first processed in a cotton gin to remove the seed and a great deal of the trash picked up with the bolls. The cotton fiber output of the cotton gin is typically called lint. The lint is very light, fluffy and loose, hence, for economy of transportation and storage, it is compressed to a higher density, and this compressed mass of cotton lint is called a bale. These bales are somewhat rectangular in shape for they are typically produced on platen presses.

Typically, gins produce either "gin flat" bales or "gin standard" bales, although a very few gins produce a much denser bale called the "gin Hi-D" (gin high density). The gin flat press costs approximately \$8,000 at the present time and produces a bale having a density of about 15#/cu. ft. The gin standard press produces a bale having a density of about 20-25#/cu. ft. and costs a great deal more—approximately \$25,000 at the present time, even though the bale density has increased only 5-10#/cu. ft. The gin Hi-D press is a massive piece of equipment costing approximately \$75,000 at the present time and produces a bale having a density of about 32-35#/cu. ft.

To understand the reason why these various gin presses increase so rapidly in cost, reference is made to FIGURE 9 wherein an approximate pressure-density curve *a-b* is shown for the compression of cotton. To produce a gin flat bale, the press must exert a pressure of about 150,000#. Thus, following the curve upwardly from *a*, the press exerts a force of 150,000# at point *c*, which is equivalent to a density of about 25#/cu. ft. Then, when the press is opened to permit tying of the compressed cotton with bands, the cotton expands along the line *c-d*. Due to the lay of the lint and the nature of cotton, once it has been killed or compressed, the density remains at some value, such as 7#/cu. ft. (point *d*) even without bands. However, with bands, the resultant density is about 15#/cu. ft. (point *e* on line *c-d*). Hence to produce a gin flat bale of 15#/cu. ft. density, the press must exert a force of 150,000# on an area approximately 28 in. x 55 in. Recompression of previously killed or compressed cotton substantially duplicates the expansion curve *c-d* up until the original compression curve is reached (point *c*), and thereafter

2

the cotton follows the original compression curve *a-b* upwardly.

In a similar manner, to produce a gin standard bale of 20#/cu. ft. density, a total force of about 600,000# must be exerted, and to produce a gin Hi-D bale of 35#/cu. ft. density, a total force of 2-2,500,000# must be exerted. Further, the gin Hi-D press platen has an area of about 20 in. x 54 in. and the press stroke is approximately 8 ft. 6 in. Thus, it is readily seen that the machines are huge, and extremely powerful, and accordingly the price is prohibitive.

Nonetheless, if a quantity of cotton were available, the cost might be justified. Unfortunately however, gins are typically located in small towns and the geographical area which a gin can economically serve is limited. So, very few gins can afford the gin Hi-D press, even though it produces a more economically shipped and stored bale. Consequently, the majority of gins produce a gin flat bale which is sent to the compress for further densification. At the compress more cotton is available, hence larger equipment is justified.

From the foregoing, it is seen that it would be very advantageous to provide a small press, simply made, relatively inexpensive, which is capable of exerting at least 2,000,000# force on cotton lint in such a manner as will produce a very high density bale. Such a press could then be economically installed at the gin to provide bales for export and domestic use, and the need for the compress would be eliminated, except perhaps as a warehouse. These, then, are the general objects of the present invention.

Previously, presses have been suggested and built which produce a round bale or a long cylinder of cotton, by rolling a continuous length of batting. Patented examples showing these round bale presses are: Treese, 653,191; Treese, 980,706; Brown, 1,257,798; Mackenzie, 1,834,466; and Mackenzie, 1,881,774. The round bale so produced was quite effective from the ginners' standpoint, but was unacceptable to the textile mills due to the matted fiber produced in the center of the bale.

The present invention is directed to a rotary press which incorporates a drum about which the cotton lint is wound and compressed. Thereafter, this compressed cotton lint is removed from the drum and placed in a small banding press for the attachment of bands. The resultant bale is rectangular in cross-section, and its density is superior to that of the gin Hi-D bale. The entire rotary press is quite small and the bale produced therefrom is uniform, without matted fibers.

In addition to utilizing the present invention as a rotary press, a smaller version thereof is ideally suited for use as a lint sampler. Cotton is one of the few commodities still purchased by samples. This necessitates hiring expert Samplers in each cotton producing area to grade the baled cotton as to quality. It is customary for the Sampler to cut the burlap protective cover on each bale and remove a large sample plug of cotton. This plug is then examined and graded, and it is assumed that the plug adequately represents the remainder of the bale. If the once plugged bale is not then sold, it will be left in a warehouse until another potential buyer is found. Again the plugging and grading is repeated, until the bale is sold. By this time, it is not unusual for the price of the bale to decline because of its mangled condition after being repeatedly plugged.

Prior devices to solve this problem have been developed which intermittently remove bursts of cotton lint from the flue between the gin machine and the baling press, condense the lint, tramp it, and finally insert a dozen or so layers into a paper wrapper. These devices were developed by the U.S. Department of Agriculture.

Because the cotton is sampled intermittently, the sample does not contain a portion of all of the lint in the bale, nor does a cross-section of the paper-wrapped sample represent a similar cross-section of the bale. Since the price of the bale is determined by the quality of the sample, it is very advantageous to provide a truly representative sample. Such a sample should contain a portion of all of the fiber in the bale, it should be compressed as is the bale, it should have the same fiber lay, and the bale should not be disturbed when grading the sample. The lint sampler of the present invention meets all of these requirements, and is additionally small, simple, easily repaired, and requires very little control equipment. Further, the lint sampler utilizes a smaller sample valve in the lint flue which opens only once.

The lint sampler of the present invention is directed to a rotary press which incorporates a drum about which the cotton lint is wound and compressed. Thereafter, the compressed cotton lint is removed from the drum and placed in a sample bag or paper wrapper. The lint sampler gathers and compresses cotton fiber virtually the entire time that the corresponding bale is being formed either on a rotary press or conventional platen press.

It is, therefore, an object of the present invention to provide a rotary press and lint sampler which has all of the advantages hereinbefore mentioned and overcomes the disadvantages of the prior devices.

Another object of the present invention is to provide a small press capable of exerting 2,000,000# force on cotton lint in such a manner as will produce a very high density bale with unmatted fibers.

Yet another object of the present invention is to provide a rotary press having a drum which produces a circular band of compressed fiber.

Another object is to provide a rotary press having a drum from which compressed fiber may be easily and readily removed, and converted into elongate batts for the formation of a rectangular cross-section bale or for insertion into a sample wrapper.

A still further object of the present invention is to provide a novel means for the removal of a compressed ring of fiber from the drum of a rotary press.

Another object of the present invention is to provide a rotary press whereby the pressure necessary to form a highly compressed fiber batt need be applied to only a small part of the fiber at any one time, thus substantially reducing the total force, size, and complexity of the press.

Another object of the present invention is to provide a fiber press which requires no surges of energy and which employs a mechanical drive with components familiar to ginners and without the need for fluid pressures and attendant oil stains.

Other and further objects, features and advantages will be apparent from the following description of presently preferred embodiments of the invention, given for the purpose of disclosure, taken in conjunction with the accompanying drawings, where like character references designate like parts throughout the several views, and where:

FIGURE 1 is a schematic representation of the flow of cotton in a gin, showing the present invention utilized as a lint sampler,

FIGURE 2 is a schematic representation of one form of ejection mechanism for compressed batts of the present invention,

FIGURE 3 is a view similar to FIGURE 2 showing the compressed ring-like batt being cut,

FIGURE 4 is a view similar to FIGURE 2 showing the batt being ejected,

FIGURE 5 is a rear view of a lint sampler according to the present invention,

FIGURE 6 is a side view of the device of FIGURE 5, FIGURE 7 is a front view of the device of FIGURE 5, FIGURE 8 is a schematic representation of one form

of drive for the compression rollers of the device of FIGURE 5, and

FIGURE 9 is a pressure density curve of cotton fiber showing the effect of compression and expansion.

Generally, the apparatus of the invention comprises a drum whose circumference is surrounded by a series of compression rollers. In addition, means are provided for the ejection of a ring-like batt of compressed fiber, such as by cutting the ring and then running the batt out.

The theory of the invention is quite readily seen by referring to FIGURE 9, and the prior discussion thereof hereinabove. Briefly, cotton fiber when compressed follows the curve *a*-*b* upwardly. This curve is derived from data obtained when compressing bales of cotton in hydraulic presses. As previously noted, if the cotton fiber is compressed until a certain pressure is reached, such as at *c* and then the pressure is removed, the cotton gradually expands along the line *c*-*d*. Therefore, the density has increased even though the pressure is removed, for the density at *d* is greater than that at *a*. Further, if the once compressed fiber is recompressed it substantially follows the curve *d*-*c* until intersecting the original curve *a*-*b*, hence the recompression curve would be *d*-*c*-*b*. A similar family of expansion and recompression curves exists all along the curve *a*-*b*.

If the cotton fiber is compressed along *a*-*b* to *c*, then removed from the press, it expands down to *d*. Thereupon, the compressed fiber (now a batt) is placed in a small press for banding and a comparatively small amount of pressure again applied (such as that indicated by the horizontal dashed line labeled "band holding force") and the density is again increased to that at point *e*. This may be conveniently done in a small conventional banding platen press.

Thus it is seen that the problem is to effect a substantial first compression along the curve *a*-*b*, with much smaller equipment than heretofore used. Therefore, the present invention applies a very high pressure to a small area of the cotton fiber by wrapping the cotton lint about a drum and compressing the lint between the drum and a series of rollers disposed about the drum. Thereupon, means are provided for the removal of the compressed ring of cotton from the rotary press. The discussion which follows is first directed to a lint sampler for compressing and packaging a sample of cotton lint which may be used for grading a contemporaneously formed bale. Then the discussion will turn to additional forms of the rotary press for particular use in bale forming instead of sampling, although all may be used interchangeably.

Referring now to FIGURE 1, a generalized schematic view of the flow of cotton lint in a gin is shown. The trash is removed and the incoming cotton bolls are then deseeded in the conventional gin machine 20. Then the cotton is conducted to the conventional gin press 22 through a lint flue or conduit 24. The lint may be carried by a positive pressure (such as by blowers) or by a vacuum system, both of which are conventional, and a condenser 26 is used to remove the air and leave an uncomressed mat of fiber. This mat is built up in layers in a conventional gin press 22, and then compressed into a bale.

A sample valve 28 is provided in the flue 24 for the removal of a sample of cotton lint which will be made into a packaged compressed sample. A conventional sample valve 28 is shown in the patent to Gaus et al., No. 2,320,544. Leading from the valve 28 is a duct 30, which may be a flexible hose, that carries a small part of the airborne lint 32 to the lint sampler 34. The lint sampler 34 includes condenser rollers 36, guide rollers 38 immediately downstream from the condenser rollers 36, and a drum 40 surrounded by compression rollers 42. Associated with the drum 40 is a means of removing the compressed batt, hereinafter described. The cotton batt 44 leaving the condenser rollers 36 is shown as a mat defined by two solid lines for ease of explanation.

The condenser rollers 36 turn inwardly toward each other, as indicated by the arrows, and remove the air which carries the lint 32. In a conventional manner, therefore, the condenser rollers 36 provide a loose batt 44 of cotton fiber which is fed to the guide rollers 38. The guide rollers 38 also rotate inwardly to provide a slight firming up or compression of the batt 44 and also to feed the batt 44 onto the drum 40. The drum 40 rotates in a certain direction, such as that indicated by the arrow, and likewise the compression rollers 42 rotate with substantially the same peripheral speed as the drum 40, so that the batt 44 is fed and wound about the drum 40. The compression rollers 42 are spaced from the periphery of the drum 40 a small distance to allow the batt 44 to pass therebetween. In a conventional manner, some or all of the compression rollers 42 may be knurled, toothed, splined, or the like to aid in winding the batt 44 upon the drum 40. In a spiral manner, the successive layers of the batt 44 are built up on the drum 40. As the thickness of the wound batt 44 increases, the compression rollers 42 begin to compress the batt 44.

The compression of the wound batt 44 continues until either the gin press 22 is full and the lint in the lint flue 24 is shut off upstream from the valve 28, or until the lint sampler 34 is shut down due to reaching its capacity, or until the lint from the gin machine 20 is diverted through appropriate conventional means to a similar gin press 22 and lint sampler 34 or a conventional accumulator (not shown). In any event, as a mere matter of design, the capacity of the lint sampler 34 is designed so that the compression on the batt 44 is substantially equivalent to that of a normal bale being formed in the gin press 22, and this desired compression is designed to be reached at approximately the same time as the condenser 26 for the gin press 22 is shut down. Therefore, advantageously, the valve 28 is opened only once and remains open thereafter substantially the entire time the bale is being formed in the gin press 22. It is readily seen, therefore, that the batt 44 compressed by the lint sampler 34 contains a sample portion of virtually all of the cotton in the bale, and also provides a batt 44 which is compressed in layers just as the bale. Further, the lay is similar to the bale and unmatted, for compression occurs in only one direction.

Referring again to FIGURE 9, it is seen that the pressure needed to form a high density bale increases rapidly. The pressure is, of course, defined as the force divided by the area. Therefore, in a conventional platen press if it is necessary to produce 2-2,500,000# force on a platen area of 20 in. x 54 in. to form a gin Hi-D bale, the resultant pressure needed is roughly 300,000 pounds per square foot (p.s.f.). Now, if the area of compression is substantially reduced and the resultant pressure needed remains the same, i.e., roughly 300,000 p.s.f., then the necessary force is likewise substantially reduced. Thus, if the area of compression is reduced to 20 in. x 1/4 in., the necessary force is reduced to roughly 10,000#, and the resultant pressure remains 300,000 p.s.f. In this manner, a substantial reduction in force has occurred, and the size of the press may be accordingly reduced.

As shown in FIGURE 1, the compression rollers 42 surround the drum 40. The batt 44 being compressed is disposed therebetween. The theoretical area being compressed is only the line of contact between the compression roller 42 and drum 40, and this line is as long as the roller 42 with no appreciable width. The actual area, however, is the length of the roller 42 and a finite width, and it is obvious that the highest pressure is exerted on the batt 44 at its intersection with a plane through the centers of the drum 40 and roller 42. In any event, the force necessary to compress the batt is reduced.

When the lint 32 coming from the valve 28 is shut off, the batt 44 is immediately wound and compressed around the drum 40, and becomes a ring of compressed cotton fiber. This ring must then be removed from the

drum 40 and converted into an elongate batt for insertion in a wrapper. Referring now to FIGURES 2-4, one means for doing so is shown. Briefly, this means comprises cutting the ring and running the batt 44 off of the drum.

One sector of the circumference of the drum 40 is composed of a cutter 46 having the same width as the drum 40. The cutter 46 is pivoted about the axis 48, and includes two cylindrical surfaces 50 and 52. Surface 50 has the same radius as the drum 40 so that when this surface 50 is exposed, the perimeter of the drum 40 defines a circle, such as shown in FIGURE 2. Surface 52, however, is designed to bulge outwardly when exposed on the drum 40, as in FIGURE 3, so that the spacing between the compression roller 42 and the exposed surface 52 is less than that between the drum 40 and compression roller 42. Pivotably attached to the cutter 46 is a connecting link 54 and pivotably attached to the link 54 is a crank 56. The crank 56 may be rotated through the axis of the drum 40.

To cut the batt 44 and remove it from the lint sampler 34, the rotation of the drum 40 and compression rollers 42 is stopped, with the cutter 46 opposite compression roller 42a. Thereupon, one of the compression rollers 42b is pivoted outwardly from the drum 40. Then the rotation of the compression rollers 42a and 42b is reversed. At the same time, the crank 56 is rotated to move the link 54 which rotates the cutter 46 about the axis 48. In this manner, the surface 50 is withdrawn into the drum 40 and the bulging surface 52 is exposed. Compare FIGURES 2 and 3. Since compression roller 42a is the only rotating roller now contacting the batt 44, and since the spacing between the roller 42a and the cutter 46 is reduced, the rotating roller 42a tears or cuts the batt 44 along the width of the drum 40, as shown in FIGURE 3.

Roller 42a continues to rotate, and begins to rotate the drum 40 through the batt 44. After a slight rotation of the drum 40, the crank 56 is again rotated to retract the bulging surface 52 and re-expose surface 50, thereby making the surface of the drum 40 a circular cylinder again, as shown in FIGURE 4. The compression roller 42c immediately below the pivoted roller 42b, is now rotated in a direction opposite to that of rollers 42a and 42b, so that the leading edge of the batt 44 is ejected outwardly between roller 42b and roller 42c, as seen in FIGURE 4. After one revolution of the drum 40, the batt 44 is completely ejected.

Thereupon, the ejected batt 44 is led through appropriate discharge rollers 58 (seen in FIGURE 7) and into a rectangular wrapper or sack 60. In a few seconds, the discharged cotton batt 44 begins to expand and fills the sack 60. The sack 60 is then removed from the lint sampler 34, and the operation is complete. A sample batt has been made which contains a portion of virtually all of the lint which makes up the bale, the sample has been compressed in layers, the fiber lay resembles the bale and is unmatted, and the equipment utilized is relatively simple.

Now that the theory of operation and generalized schematics have been presented, an embodiment of the lint sampler 34 of the present invention will be discussed. A presently preferred embodiment is shown in FIGURES 5-7. Referring now to FIGURE 5, the lint sampler 34 generally includes a frame 62 on which are rotatably mounted the condenser roller pulleys 136 which are directly connected to the condenser rollers 36, the guide roller pulleys 138 which are directly connected to the guide rollers 38, the drum pulley 140 which is connected to the drum 40, and the compression roller gears 142 which are connected to the compression rollers 42, all in a conventional manner. The condenser roller pulleys 136, guide roller pulleys 138, idler 64, adjustable idler 66, and a pulley 68 (shown in FIGURE 8) are interconnected by a belt 70, in such a manner that the

pulleys will rotate in the direction shown by the arrows when feeding a batt to the drum. The adjustable idler 66 is rotatably mounted on a plate 72 which is pivotably mounted at 74 on the frame 62. The plate 72 includes an arcuate slot 76 through which a bolt 78 is attached to the frame 62. When the bolt 78 is loosened, the plate 72 may be pivoted to tighten the belt 70.

A pulley 80 is attached to the jack shaft 82 and connected by a belt 84 to a motor 86. The jack shaft 82 in turn moves the belt 88 to rotate the drum pulley 140, and therefore the drum 40. Shown in FIGURE 7 is an appropriate drum gear 92 connected to the drum pulley 140 to drive the compression roller gears 142 and therefore the compression rollers 42. An identical drum gear 92 is shown in FIGURE 7. Surrounding the upper part of the condenser rollers 36, which cannot be seen in FIGURE 5 because of the condenser roller pulleys 136, is a seal 90 which is typically used in positive pressure type condensers. A similar seal 90 and the condenser rollers 36 are clearly shown in FIGURES 6 and 7.

Referring now to FIGURE 7, the front of the lint sampler 34 is shown. The drum gear 92 engages the compression roller gears 142. Since the compression rollers 42 are closely spaced, as previously shown in FIGURE 1, alternate compression rollers 42 are driven from opposite sides, although they may be driven from the same side (Treese 653,191, supra). Mounted on the upper part of the frame 62 are the condenser rollers 36, and immediately below them are the guide rollers 38, shown in dotted lines. The motor 86 is also shown in dotted lines, as are the discharge rollers 58.

Pivotably mounted on the frame 62 is a lever 94 to which are attached eccentric cams 96 and crank 98. The cams 96 are utilized to clamp the sack 60 to the lint sampler 34 by actuating two clamps 100, here shown as angle irons. Referring now to FIGURES 5 and 6, the clamps 100 are clearly shown. The clamps 100 are pivoted to the frame 62 at points 102. When the lever 94 is pulled, it rotates in the frame 62 and turns each cam 96. The cams 96 in turn pivot the clamps 100 about the pivot points 102. In this manner, the clamps 100 are moved toward or away from a funnel or chute 104 beneath the discharge rollers 58. The sack 60 is fitted about the funnel 104 and held thereon when the lever 94 is actuated to move the clamps 100 against the top of the sack 60 and the funnel 104. The funnel 104 is best seen in FIGURE 8.

The lever 94 also actuates the previously discussed cutter 46. The crank 98 is pivotably attached to the link 106 (see particularly FIGURE 7), which is in turn attached to the disk 108. The disk 108 through an appropriate clutch (not shown) is operatively connected to the crank 56, previously discussed with reference to FIGURES 2 and 3. Therefore, pulling the lever 94 also rotates the crank 98 which moves the link 106 to rotate the disk 108. Rotation of the disk 108 thereupon actuates the crank 56 and link 54, to pivot the cutter 46, thereby exposing the bulging cutter surface 52.

Still a third function is performed by the lever 94. When the sack 60 is attached, and the cutter 46 rotated for the cutting operation, then the compression roller 42b is pivoted outwardly from the drum 40. Particular reference is now made to FIGURE 8, wherein the lever 94 and part of the gearing and pulleys for the drum 40, compression rollers 42, guide rollers 38, and discharge rollers 58 are shown. Thus the compression rollers 42 are immediately attached to the compression roller gears 142, the discharge rollers 58 to the discharge roller gears 158 and the like. Keyed to the lever 94 is a crank 110, which is pivotably attached to the link 112, which in turn is pivotably attached to the bell crank 114 which is pivotably attached to the link 116, which is in turn pivotably attached to the compression roller 42b. The compression roller 42b and its gear 142b are pivotably attached to the compression roller 42a and its gear 142a,

as by the link 118. Therefore, pulling the lever 94 results in pivoting the compression roller 42b and its gear 142b, as shown by the pivoted position in dotted lines in FIGURE 8 and the addition of prime marks. Thus, pulling lever 94 rotates crank 110 to 110', moves link 112 to 112', rotates bell crank 114 to 114', pulls out link 116 to 116', and therefore pivots gear 142b to 142b' away from the drum.

Finally, movement of the lever 94 may also reverse the motor 86 or associated gearing to change the direction of rotation of the drum 40 from compression to ejection of the batt 44. Likewise, it is obvious that each of the functions of the lever 94 may be performed by separate levers or other means within the skill of the art.

From the foregoing, it is felt that the operation of the present invention as a lint sampler 34 is apparent. Briefly, then, the valve 28 is opened to admit airborne lint 32 to the condenser rollers 36 which remove the air and from a loose batt 44. This batt 44 is firmed and guided to the drum 40 by the guide rollers 38. Thereupon, the batt 44 is compressed about the drum 40 by the compression rollers 42. When the main bale is finished, the valve 28 is closed and the remainder of the batt 44 quickly wound and compressed. Thereupon the motor 86 is stopped and the lever 94 pulled. This pivots the compression roller 42b away from the drum 40; exposes the surface 52 of the cutter 46 to the action compression roller 42a; and clamps the sack 60 to the funnel 104. Then, through appropriate gearing, the rotation of the roller 42a begins in the opposite direction and cuts the batt 44. The surface 52 of the cutter 46 is withdrawn and replaced again with surface 50. The compression roller 42c begins to turn in a direction opposite to the drum 40 rotation and leads the cut batt 44 to the discharge rollers 58. The discharge rollers guide the compressed batt 44 into the sack 60. Thereafter, a return of the lever 94 to its original position releases the sack 60 with the compressed sample therein, and prepares the lint sampler 34 for another cycle.

Obviously more or less compression rollers may be utilized than those shown, and the width of the drum increased or decreased as needed, all being within the skill of the art. Likewise, the motor need not be mounted on the frame, nor need it be a motor at all, for the lint sampler may be actuated by an existing jackshaft in the cotton gin.

When it is desired to utilize the present invention as a rotary press for the production of full size bales, it is readily apparent that the type of drum previously discussed is quite adaptable therefor. In this instance, the rotary press would replace the large gin press 22 shown schematically in FIGURE 1. The rotary press would make a large number of compressed batts which would thereupon be stacked together on the platen of a small banding press. The banding press need not be a powerful machine, for reasons that will be apparent from another look at FIGURE 9. When the rotary press compresses the cotton along the curve from *a* to *b*, and then ejects the compressed batts, they will expand downwardly along the curve *b-f*. However, the cotton batts, even at point *f*, retain a considerable density, in the nature of 25#/cu. ft. Thereafter, to recompress the once compressed batts, the banding press need only exert the small force represented by the horizontal dashed line (point *g*) to provide a bale having a density of approximately 35#/cu. ft. In this manner, a small banding press and the rotary press of the present invention have completely replaced the huge 8'6" stroke gin Hi-D platen press. The banding press will represent no additional outlay to the ginner, for such small presses are also utilized to band bales made by conventional gin platen presses.

Thus it is seen that the present invention provides a simple, yet effective, means for the formation of highly compressed cotton batts which may be utilized for the formation of bales or as a lint sampler.

As the theory of operation has been previously disclosed, the method of the present invention is believed to be apparent. The method is not intended to be limited to the apparatus embodiment shown. Briefly, the method of the present invention includes the condensation of airborne lint into a loose fibrous batt. Thereupon, the batt is wound upon a suitable drum and compressed between the drum and a series of compression rollers disposed about the drum. The compressed batt is quite dense, for the reasons previously given with reference to FIGURE 9. The compressed batt is then ejected from between the drum and compression rollers, by cutting the batt, and led into a wrapper or sack for use as a sample, or placed on a small banding press with similar compressed batts for the formation of a banded bale.

The present invention, therefore, is well adapted to carry out the objects and attain the ends and advantages mentioned as well as others inherent therein. While a presently preferred embodiment of the invention has been given for the purpose of disclosure, numerous changes in the details of construction, and the combination, shape, size, arrangement of parts, and uses may be resorted to without departing from the spirit and scope of the invention as hereinafter claimed.

What is claimed is:

1. In a batt compressing rotary press, a rotatable non-adhesive batt winding drum, a series of rotatable compression rollers surrounding and spaced in fixed relationship from the periphery of said drum, means for rotating said drum and rollers in the same rotary direction at substantially the same peripheral speed, batt forming means for forming cotton into a loose batt and introducing it between one of said rollers and said drum, whereby rotation of said drum and rollers winds said batt upon the periphery of said drum and compresses said batt between said drum and rollers, a pivotable cutter mounted in a sector of the periphery of said drum, said cutter including a circular surface and a bulging surface, means for pivoting said cutter to expose said circular surface when winding and compressing a batt and for pivoting said cutter to expose said bulging surface when cutting said batt for ejection after compression, and means for rotating said compression rollers and drum to eject said compressed batt after cutting.

2. The invention of claim 1 including one of said compression rollers being pivotably mounted adjacent said drum, and means for pivoting said compression roller

away from said drum when said bulging cutter surface is exposed and said compressed batt is being ejected.

3. The invention of claim 2 including rotatable guide rollers disposed adjacent said pivotable compression roller, and means for rotating said guide rollers and compression rollers and drum to eject said compressed batt after cutting between said guide rollers and from said rotary press.

4. In a batt compressing rotary press, a rotatable non-adhesive batt winding drum, a series of rotatable compression rollers surrounding and spaced in fixed relationship from the periphery of said drum, means for rotating said drum and rollers in the same rotary direction at substantially the same peripheral speed, a condenser and guide rollers disposed adjacent said drum for forming a loose batt and introducing said bat between said drum and one of said compression rollers, whereby said batt may be wound upon said drum and compressed between said drum and said compression rollers, a pivotable cutter mounted in a sector of the periphery of said drum, said cutter including a circular surface and a bulging surface, means for pivoting said cutter to expose said circular surface when winding and compressing a batt and for pivoting said cutter to expose said bulging surface when cutting said batt for ejection after compression, one of said compression rollers being pivotably mounted for pivoting away from the periphery of said drum when ejecting said batt, discharge rollers disposed adjacent said pivotable compression roller, means for rotating said pivotable compression roller and an adjacent compression roller in opposite rotary directions for guiding the said batt during ejection from said drum to said discharge rollers, means for rotating said discharge rollers in opposite rotary directions for discharging said compressed cut batt from said rotary press, and means for rotating said drum and the remaining compression rollers in the same rotary direction as the pivoted compression roller when ejecting said compressed batt.

5. The invention of claim 4 including a funnel disposed beneath the said discharge rollers, and clamp means adjacent said funnel for holding a sack into which said ejected batt is slid.
